DESIGN FOR A FIREMAN'S SAFETY COAT OR SIMILAR ARTICLE

Harry J. Callahan, Detroit, Mich.

Application October 25, 1939, Serial No. 87,858

Term of patent 7 years

To all whom it may concern:

Be it known that I, Harry J. Callahan, a citizen of the United States, residing at Detroit, in the county of Wayne and State of Michigan, have invented a new, original, and ornamental Design for a Fireman's Safety Coat or Similar Article, of which the following is a specification, reference being had to the accompanying drawing, forming part thereof.

In the drawing:

Fig. 2 is a rear view of the fireman's safety coat shown in Fig. 1.

The characteristic feature of my design resides in the combination on the fireman's safety coat disclosed of the specific contrastingly colored bands arranged on the body and sleeves as shown.

I claim:

The ornamental design for a fireman's safety coat or similar article, as shown and described.

HARRY J. CALLAHAN.
